UNITED STATES PATENT OFFICE.

ALEXANDER JOHN O'BRIEN, OF BELOIT, WISCONSIN, ASSIGNOR OF ONE-HALF TO CHARLES A. GAULT, OF BELOIT, WISCONSIN.

OIL-BURNER.

SPECIFICATION forming part of Letters Patent No. 741,820, dated October 20, 1903.

Application filed March 30, 1903. Serial No. 150,217. (No model.)

To all whom it may concern:

Be it known that I, ALEXANDER JOHN O'BRIEN, a citizen of the United States, residing at Beloit, in the county of Rock and State of Wisconsin, have invented certain new and useful Improvements in Oil-Burners; and I do declare the following to be a full, clear, and exact description of the invention, such as will enable others skilled in the art to which it appertains to make and use the same.

This invention relates to improvements in hydrocarbon or oil burners.

The object is to provide a burner of this character which can be used for generating heat in hot-air furnaces, stoves, hot-water heaters, steam-boilers, and the like.

Another object is to provide improved means for heating the oil, removing the impurities, and converting the same into gas before reaching the burners.

With these and other objects in view the invention consists of certain novel features of construction, combination, and arrangement of parts, as will be more fully described, and particularly pointed out in the appended claims.

In the drawings, Figure 1 is a side view of the burner complete. Fig. 2 is a vertical longitudinal sectional view of the same. Fig. 3 is a cross-sectional view; and Fig. 4 is a view similar to Fig. 1, showing the burner inclosed in a casing or box.

In the drawings, 1 denotes the oil-tank; 2, the oil-feed pipe, provided with a valve 3 for regulating the flow of oil from the tank.

4 denotes the generator or retort, which has a flat top and a vertical side and is cut away on one side on a curve to form a depending flange 8 and an overhanging shoulder 5. The retort has a longitudinal retort-passage formed in its upper portion arranged for the connection of the feed or supply pipe at one end. A vapor-discharge tube 10 is connected to the other end of the said passage and ends in the horizontally-disposed pipe 9, arranged beside the depending flange and beneath the overhanging shoulder of the retort or generator and provided with a series of burner openings or jets 12, which are arranged to discharge the gas or vapor against the curved portion of the retort. The same

being ignited effects the thorough heating of the retort and its passage, as will be understood. The depending flange 8 on the rear side of the retort or generator forms a shield or wall for the purpose hereinafter stated.

Beneath the burner-tube is arranged a drip-trough 13, into which a small quantity of oil may be run and lighted to start the generator.

In Fig. 4 the generator and burner-pipe are shown inclosed in a sheet-metal box or casing 14, open at its upper side, and in the conical shaped bottom thereof is formed a centrally-disposed opening 15, surrounded by a fixed, downwardly-extending, and flaring flange 16, an annular series of holes 17 also being formed through the bottom, as shown. The purpose of the casing is to create a suction of air into its lower end and discharge the same in a blast at its upper open end. 70

The construction of the generator, as herein shown, with a rear shield or wall is for the purpose of deflecting or directing the flame up and around the body of the same to constantly heat the oil-passage therein and to prevent the draft through furnace or stove from blowing the flame from the burners away from contact with the generator. The carbon lining in the passage 6 has a catalytic action on the oil in its conversion into vapor 80 and being porous acts as a sieve to catch the impurities and prevents clogging up of the burner-pipe.

From the foregoing description, taken in connection with the accompanying drawings, the construction and operation of the invention will be readily understood without requiring a more extended explanation.

Various changes in form, proportion, and the minor details of construction may be resorted to without departing from the principle or sacrificing any of the advantages of this invention.

Having thus described my invention, what I claim, and desire to secure by Letters Patent, is—

1. In combination with a burner, a retort having a passage formed therein for vaporizing oil to be supplied to the burner, and a lining-tube of porous carbon in said passage, substantially as described.

2. A horizontally-arranged retort having a

flat top and vertical side, and cut away on one side on a curve to form a depending flange portion and overhanging shoulder, having a retort-passage formed in its upper portion arranged for the connection of a supply-pipe at one end, and a vapor-discharge tube connected to the other end of said passage and ending in a horizontal pipe arranged beside said depending flange and beneath the overhanging shoulder and provided with a series of burner-openings arranged to discharge against the curved portion of the retort, substantially as described.

3. A horizontally-arranged retort having a flat top and vertical side, and cut away on one side on a curve, to form a depending flange portion, and an overhanging shoulder, having a retort-passage formed in its upper portion arranged for the connection of a supply-

pipe at one end, and a vapor-discharge tube 20 connected to the other end of said passage and ending in a horizontal pipe arranged beside said depending flange and beneath the overhanging shoulder and provided with a series of burner-openings arranged to discharge 25 against the curved portion of the retort, in combination with a casing inclosing said retort and discharge-tube and provided with a downwardly-extended neck portion having air-inlet openings therein, substantially 30 as described.

In testimony whereof I have hereunto set my hand in presence of two subscribing witnesses.

ALEXANDER JOHN O'BRIEN.
